MAX WURM, OF BROOKLYN, NEW YORK

EXTENSION TABLE

Application filed December 16, 1932. Serial No. 647,569.

My invention relates in general to means for extending temporarily the working or service surface of a cooperating member and it is especially applicable to the type of extension tables having a fixed top-member which is to be extended in service at one or more of its edges, such for example, as the refectory style of table.

An important advantage possessed by my improvements is that of extreme simplicity; also that of minimizing the amount of hardware necessary for mounting and operating the extension leaf; also the facility of quick and smooth operation of the mechanism in the movements of bringing the adjustable leaf into position of service and returning it to stored position. There are other advantages to be derived from the use of my improvements, as will appear from the detailed description hereinafter given in connection with the drawing.

I have illustrated types of my invention in the accompanying drawing, wherein:—

Figure 1 shows a top plan view of an extension table provided with my improvements; the upper part of the figure showing the folding extension leaf as drawn out with its slides from stored position, in place to be swung upwardly and outwardly over the slides and the apron carried thereby and in position to be then slid inwardly into abutting relation with the top-member, which latter condition is shown at the bottom of the figure.

Figure 2 shows a view in vertical cross-section of the structure shown in Fig. 1, the plane of the section being indicated by line 2—2, in Fig. 1.

Figure 3 shows a vertical cross-sectional view of a portion of the structure shown in Figs. 1 and 2, but with the folding extension leaf folded down and slid under the top-member in stored position.

Referring to the drawing, in which like numerals of reference designate like parts throughout, 1, 1, indicate parallel bridge pieces to the respective ends of which are secured vertical aprons 2 and 3, which depend from the respective ends of the table top-member 4, to which they are secured.

Upon the bridge pieces are secured transverse horizontal guides 5 and 6.

At the opposite long edges of the top-member 4, are mounted folding extension leaves 7 and 8, respectively. The leaf 7 is mounted to swing substantially through a half-circle on a horizontal axis which lies parallel with the long edge of the top-member which it extends. The leaf 7 is moved in response to the movements of the horizontal reciprocation of the slides 9 and 10, mounted respectively upon the inner faces of the guides 5 and 6. Upon the outer ends of the respective slides 9 and 10, is secured a vertical apron 11, which cooperates with aprons 2 and 3, and top-member 4, when they are moved to their inner limit of movement. The axis of motion of leaf 7 is at right-angles to the direction of movement of the sliding means and is located between the outer end thereof and the leaf. The construction and arrangement is such as to permit of the leaf being folded inwardly towards the top-member with its underside uppermost in stored position and also folded outwardly away from said top-member with its underside uppermost when abutting the top-member in position of service. This may be accomplished by use of ordinary hinges which I have here shown as comprising a pair of plate hinges secured between the leaf 7, and the movable means to the movements of which the leaf responds. The plate 12, of one hinge is attached to slide 9, and its mate 13 is attached to the flat surface of the underside of the leaf 7. The plate 14, of the other hinge, is attached to the other slide 10, and its mate 15, to the flat underside of the leaf. The axial line of the hinges is such that the leaf may be swung in the way just described. In the present construction the axis of motion afforded by the hinges lies between the respective points of attachment of the hinges to the leaf and the slides and in a plane slightly above the level of the underside of the leaf. One end of each hinge may if preferred be mounted directly upon the apron 11, which is virtually a part of the sliding means. With this arrangement, when the leaf is folded down in position of

storage, the hinge is unfolded or open and when the leaf is folded outwardly into position of service, the hinge is folded up or closed.

5 The leaf 7, when swung towards the top-member with its upper side down upon the slides, as shown in Fig. 1, at the upper part thereof, may then be stored under such member by pushing the slides in to their inward 10 limit of movement and this will bring the apron 11 against the respective ends of aprons 2 and 3 and beneath the edge of the top-member, as shown in Fig. 3. In order to adjust the leaf 7, in place for service to 15 extend the top-member, the apron 11 is pulled upon so as to draw it and the slides outwardly, and when in the position shown at the upper part of Fig. 1, and the right-hand side of Fig. 2, the leaf is swung upwardly away from the member, as indicated in dotted lines in Fig. 2, and until it is folded down upon apron 11, whereupon the apron and slides are pushed inwardly to bring the edge of the leaf into abutting relation with 20 the edge of the top-member, as shown in both of said Figs. 1 and 2. It will be noted that the axis of motion of the leaf 7 is so located relatively to the apron 11, that when the leaf is adjusted in the plane of the top member 25 in position of service, it rests upon the edge of the apron at about the center of the width of the leaf and thereby provides a stable construction which will withstand pressure upon the outer edge of the leaf when in service. 30 This axis is located also quite near the apron, thereby reducing the range of movement outwardly of the sliding means and apron, when bringing the leaf into position to be swung up; the nearer this axis to the apron, 35 the less the range of outward movement.

The leaf 7 is so hinged that the axis of motion lies just off the flat surface of the leaf and overhangs the bevel 16, at the edge of the leaf, so that the plates 13 and 15, of the respective 40 hinges, take under the abutting edge of the top-member and engage the same in locking relation against upward movement of the abutting edge of the leaf, as indicated in Fig. 2, at the left-hand side thereof. The bevel 45 16 of the leaf is formed in counterpart to the bevel 17, of the top-member, so that a snug fit is provided between the abutting edges thereof. As this pair of ordinary stock 50 hinges constitutes the entire hardware of the structure, an extremely simple and inexpensive construction is thereby provided, and in cases where the hinges are of a size two by one and one-eighth inches, the length of the bearing of the hinge joints affords a stable and 55 firm construction which will give true movement in the swinging adjustment of the leaf and avoid wobbling thereof.

Each of the slides 9 and 10 is formed upon its upper side with a downwardly 60 extending recess or cut-away place 18, direct-

ly below the leaf hinges, for the purpose of giving full clearance to the hinged end of the leaf in the swinging movements thereof.

The extension leaf 8 is constructed and arranged like leaf 7, having a pair of slides 19, 70 20, mounted respectively upon the outer faces of the guides 5 and 6, and having an apron 21, secured thereto. The leaf 8 is provided with a pair of hinges 22, arranged in the same manner as that described in reference to the 75 hinges of leaf 7, and the operation of leaf 8 is identical with that of leaf 7.

Having thus described my invention, what I claim and desire to secure by Letters Patent, is:—

1. The combination with a member whose working or service surface may be temporarily extended, of a folding extension leaf, sliding means movable with respect to said member, said leaf being mounted to swing on said 85 sliding means so that it may be folded inwardly toward said member with its underside uppermost in stored position and also folded outwardly away from said member with its underside uppermost and abutting 90 said member in position of service.

2. The combination with a top-member, of sliding means movable with respect to said member so that it may be moved inwardly beneath said member and outwardly beyond it, 95 said sliding means being provided with an apron cooperating with said member, a folding extension leaf hinged to said sliding means so that said leaf may be folded inwardly towards said member with its underside uppermost in position to be stored and folded outwardly away from said member with its underside overlying said apron and abutting 100 said member in position of service.

3. The combination with a top-member, of 105 guides beneath said member and slides mounted on said guides, a folding extension leaf mounted above said slides so as to swing on an axis at right-angles to the direction of movement of said slides and moving in response to the movement thereof, said leaf being adapted to be folded inwardly towards said member into a plane disposed between said member and slides so that it may be stored beneath said member and also adapted to be folded outwardly away from said member and into the plane thereof in abutting relation therewith in service position.

4. The combination with a member whose working or service surface may be temporarily extended, of movable means disposed below the level of said member, an extension leaf mounted to fold with respect to said member and moving in response to the movements of said movable means so that it may be adjusted into and below the plane of said member and when in the latter position to lie with its upper-face down across the movable means.

5. The combination with a top-member, of 130

- movable means disposed below the level of said top-member, a folding extension leaf mounted to swing on an axis so that it may be adjusted into and also below the level of 5 said top-member and moving in response to the movements of said movable means, the said axis of motion of the leaf being disposed below the level of said top-member when the leaf is adjusted into the plane thereof for service and disposed above the plane of said leaf when the latter is adjusted below the plane of said top-member in stored position. 10
6. The combination with a top-member, of movable means disposed below the plane of 15 said top-member, a folding extension leaf mounted to swing on an axis so that it may be adjusted into and also below the plane of said top-member and moving in response to the movements of said movable means, the 20 said axis of motion of said leaf being disposed above said leaf when it is folded with its upperside down and disposed below the plane of said top-member when said leaf is adjusted into position of use and abutting said top- 25 member.
7. The combination with a member whose working or service surface may be temporarily extended, of a folding extension leaf, sliding means movable with respect to said member, said leaf being mounted to swing on said sliding means so that it may be folded inwardly towards said member with its underside uppermost in stored position and also folded outwardly away from said member 30 with its upperside uppermost and abutting said member in position of service, the axis of motion of said leaf being disposed at or near the edge of said leaf which abuts the edge of said member when in position of service. 35
- 40
8. The combination with a member whose working or service surface may be temporarily extended, of a folding extension leaf, sliding means movable with respect to said member, said leaf being mounted to swing on said sliding means so that it may be folded inwardly towards said member with its underside uppermost in stored position and also folded outwardly away from said member 45 with its upperside uppermost and abutting said member in position of service, the axis of motion of said leaf being disposed upon the underside of said leaf at or near the edge thereof which abuts said member when 50
- 55 in position of service.
9. The combination with a top-member, of movable means disposed below the plane of said top-member, a folding extension leaf hinged upon its underside above said movable 60 means and moving in response to the movements thereof, one part of said hinge being mounted upon the underside of said leaf and the other upon a part disposed beyond the edge of said leaf which lies outermost when 65 the leaf is in stored position.
10. The combination with a top-member, of slides disposed below said top-member, a folding extension leaf mounted to swing on said slides so that it may be folded inwardly towards said member with its underside uppermost in stored position and also folded outwardly away from said member with its upperside uppermost and in the plane of said member, one part of the swinging mounting being attached to the underside of said leaf and the other part to said slides. 70
11. The combination with a top-member, of slides disposed below said member, a folding extension leaf hinged to said slides so that it may be adjusted into and below the plane of said member and moving in response to the movement of said slides, said hinge being so arranged that the articulated part thereof projects free when folded and takes under and engages the underside of said top-member when the leaf is adjusted into service position therewith. 80
12. The combination with a member whose working or service surface may be temporarily extended, of a folding extension leaf, sliding means movable with respect to said member, said leaf being hinged to said movable means so that it may be folded inwardly towards said member with its underside uppermost in stored position and the hinge unfolded, and also may be folded outwardly away from said member with its upperside uppermost in service position and said hinge then folded. 85
